G. RACE.
CLOTHES DRIER.

No. 24,575.

Patented June 28, 1859.

Inventor.
George Race.

UNITED STATES PATENT OFFICE.

GEORGE RACE, OF NORWICH, NEW YORK.

CLOTHES-DRIER.

Specification of Letters Patent No. 24,575, dated June 28, 1859.

To all whom it may concern:

Be it known that I, GEORGE RACE, of 5
Norwich, in the county of Chenango and
State of New York, have invented a new and
useful Improvement in Clothes-Reels; and
I do hereby declare that the following is a
full, clear, and exact description of the
same, reference being had to the accompanying
drawings, forming a part of this specifi-
cation, in which—

10 Figure 1, is a top view of the clothes reel
with the arms extended. Fig. 2, is a vertical
projection of the post which incloses
the arms, and Fig. 3, is a vertical longitudi-
15 nal section of the same, showing also in
red lines, the arms when extended for use.

Similar letters of reference, in each of the
several figures indicate corresponding parts.

My invention relates to that class of ma-
20 chines used for the purpose of drying clothes
or other similar articles, and consists in the
employment of a hollow post, which incloses
the arms on which the materials to be dried
rest, together with devices for raising, ex-
25 tending and lowering said arms which are
hereinafter more fully described.

To enable others, skilled in the art, to
make and use my invention, I will proceed
to describe its construction and operation.

30 In the drawings, A, represents a hollow
post which is firmly inserted in the ground.
This post A, is made hollow for the recep-
tion of the arms D, D, which are hinged at
35 their lower extremities to the head H, and
are connected together at their upper ex-
tremities by cords E, or other similar con-
nections. To the bottom of the head H, are
40 attached two pulleys y, y, around which
passes a cord or other connection. The cord
is attached to the upper end of the post A,
from thence it passes around the pulleys
45 y, y, attached to the head H, thence passes
out over pulleys at the side of the hollow
post, and around a crank shaft having its
bearings in the upper end of the hollow post.

F, is a rack on the side of the head H,
which gears into the pinion m, when the
head is elevated.

l, is a latch on the side of the hollow post

which by sliding back and forth is made 50
to gear and ungear with the pinion m, on
the crank shaft and thus secure the head
when it is elevated.

The arms D, D, being hinged to the head
H, will, when the latter is elevated, fall by 55
reason of gravity into the positions shown
in Fig. 1, while they will be retained in
such position by the cords E, E, which sup-
port the materials to be dried.

The operation of my invention is obvious: 60
Power being applied to the crank shaft, the
head with its arms D, D, is elevated in the
hollow post by the cord and pulleys de-
scribed, until the head is sufficiently ele-
vated for the pinion m, to gear into the 65
rack F on the head H; the head is then
further raised by the rack and pinion, un-
til the arms clear the hollow post when the
former being hinged to the head, fall by
70 reason of gravity into the position shown 70
in Fig. 1. The clothes are placed on the
cords connecting the arms, or on the arms
themselves. After the clothes are dried,
the arms, by a reverse movement of the
75 crank shaft may be returned to the hollow
post.

The advantages of my reel over those in
ordinary use, consist in the protection of the
80 arms and cords from the weather, when the
machine is not in use, by their being in-
closed in the hollow post; the arms likewise
afford no obstruction and require no room
when the machine is not in use, which is im-
85 portant in crowded localities, and the lines
do not have to be attached to the arms of
the reel each time that it is used.

S, is a cap which covers the hollow post
90 to protect the arms and other devices con-
tained in the post from the action of the
weather, when not in use.

What I claim as my invention and desire
to secure by Letters Patent, is—

1. The employment of a hollow post in-
closing the arms of the reel in which the
95 arms may be elevated and depressed through
its top, in the manner and for the purpose
set forth.

2. The combination of the sliding head

H, and the arms D, hinged to said head at their lower extremities and connected by cords or other equivalent connection at their upper extremities, substantially as and for 5 the purpose described.

3. The combination with the foregoing, of the cord and pulleys, the pinion *m*, rack F, and latch *l*, for elevating and securing the head H, in the hollow post, when the whole

is constructed and operated substantially in 10 the manner set forth.

The above specification of my improved clothes drier signed by me this 2d day of June 1859.

GEORGE RACE.
